CLAIM

The ornamental design for a connector housing for a printed circuit board, as shown and described.

DESCRIPTION

FIG. 1 is a perspective view of a connector housing for a printed circuit board showing my new design;

FIG. 2 is a top plan view thereof;

FIG. 3 is a front elevational view thereof;

FIG. 4 is a rear elevational view thereof;

FIG. 5 is a bottom plan view thereof;

FIG. 6 is a right elevation view thereof, the left elevation view being a mirror image;

FIG. 7 is a section view taken along line 7—7 of FIG. 3;

FIG. 8 is another section view taken along line 8—8 of FIG. 3;

FIG. 9 is yet another section view taken along line 9—9 of FIG. 3.

FIG 1
